UNITED STATES PATENT OFFICE.

GEORGE R. CONKLIN, OF NORMAN, OKLAHOMA.

ELECTRIC HEATING APPARATUS.

Application filed November 14, 1921. Serial No. 515,029.

To all whom it may concern:

Be it known that I, GEORGE R. CONKLIN, a citizen of the United States, residing at Norman, in the county of Cleveland and 5 State of Oklahoma, have invented certain new and useful Improvements in an Electric Heating Apparatus, of which the following is a specification.

This invention appertains to certain improvements in electric heating apparatus, and more particularly to a type of the same adapted to be submerged in the body of liquid to be heated, such as the saponified body of water used in washing machines. 10 15 The principal object of the invention is to provide for a heating device as characterized, and one of an extremely simple construction and arrangement, whereby to effect the heating of a body of water or other liquid to any of several desired or predetermined degrees of temperature.

Another object of the invention is to provide for a heating device of the class set forth, and one of a relatively small compact 20 25 construction, whereby to occupy a minimum amount of space in a washing machine body or other container, and at the same time, to produce maximum heating effects to the body of liquid in which it is immersed.

30 A further object of the invention is to provide for a heating apparatus of the type mentioned, and one preferably arranged for use on three wire systems of electric current distribution, whereby the separate heating 35 units of the apparatus may be connected in the circuit in a manner to effect an equal distribution of the current utilized for the heating purposes equally to both sides of such current distributing system.

40 With the foregoing and other objects in view, the invention resides in certain novel and useful construction and arrangement of parts and circuits as will be hereinafter more fully described, set forth in the appended 45 claims, and illustrated in the accompanying drawings, in which:—

Figure 1 is a perspective view of a conventional form of washing machine with the preferred embodiment of the heating apparatus applied thereto,

Fig. 2 is a vertical section taken on the line 2—2 of Fig. 1,

Fig. 3 is a diagrammatical plan view of the arrangements of electrical heating elements of the apparatus, and the circuit connections thereof, and Figure 4 is a frag-

mentary view, illustrating one of the heating units.

Referring to the drawings, the numeral 10 indicates the casing of a washing machine 60 of conventional form and preferably of a type involving a rotary cylinder or tumbler 11, having its shaft 12 journaled in bearings 13, and adapted to be driven by any suitable external power means, such as the pulley 65 and belt drive connections 14 and 15.

The heater for a washer comprises a casing 16, preferably of water-tight construction and substantially rectangular in plan, and is of a length to underlie a major portion of that of the washing cylinder or tumbler 11. Enclosed within the casing 16 is a number of heating units 17, 18, 19 and 20, four of such units only being shown at the present instance but which may be of a 70 75 greater or a lesser number if desired, each unit consisting of two sets of heating elements 17^a, 17^b; 18^a, 18^b; 19^a, 19^b; and 20^a, 20^b; connected in series one with the other, and each individual set thereof consisting of 80 85 a number of suitably arranged resistance coils or the like connected one in series with the other. The individual coils 27, are preferably wound on cores 28, of mica insulation, or the like and in any suitable or known manner, and the sets 17^a, 18^a, 19^a and 20^a of each unit 17, 18, 19 and 20, are preferably arranged in T form at 29, while the sets 17^b, 18^b, 19^b and 20^b are preferably arranged in U form at 30, whereby the vertical leg of the 90 95 T arrangement extends into the spaces between the vertical legs of the U arrangements, the outline of each unit of coils 17, 18, 19 and 20, being substantially that of a square. These units of coils are positioned within the casing 16 and are embedded in a suitable filling of insulation material, as at 31, 32 which is preferably of plastic form and capable of hardening around the unit under the action of the heat therefrom.

100 The terminal leads 17^c, 17^d; 18^c, 18^d; 19^c, 19^d; and 20^c, 20^d; from the heating units 17, 18, 19 and 20, are extended to one end of the casing 16 and lead therefrom through a conduit 21, which, in turn, passes to the outside 105 of the washer casing 10, and is inclined upwardly of the end wall of the latter in a forward direction and to a point at the upper corner thereof, where it connects with a switch casing 22, which encloses a set of 110 switch mechanisms 23, 24, 25 and 26, corresponding in numbers of that of the number

of heating units contained within the casing 16, which switch mechanisms are preferably of the so called "snap" types thereof.

The heater is preferably connected in on a three wire system of electrical distribution, consisting of the positive line conductors 27 and 28, and a negative line conductor 29, substantially as is shown in Fig. 3, and in a manner that the heating units 17 and 18, for instance, are connected across the positive line conductor 27 and the negative line conductor 29, and the heating units 19 and 20 across the positive conductor 28 and the negative line conductor 29, the circuit connections of the several heating units 17, 18, 19 and 20 being, as follows:—

The terminal lead 17^c of the heating unit 17 is connected through the switch 23 to the line conductor 27 and by a terminal lead 17^d directed to the negative lead 29; the terminal lead 18^c of the heating unit 18 is similarly connected through the switch 24 of the line conductor 27 and by other terminal lead 18^d directed to the negative line conductor 29, while the several conductors 19^c and 20^c of the heating units 19 and 20, are connected through the switches 25 and 26, respectively, to the line conductor 28 and by their other terminal leads 19^d and 20^d directed to the negative line conductor 29, so by manipulating the switches 23, 24, 25 and 26 the several heating units 17, 18, 19 and 20 may be readily cut into and out of circuit at will, and in a manner that the temperature of the wash water within the washer casing 10 is readily heated to any desired temperature accordingly.

From the foregoing, it will be readily apparent that while a preferred embodiment of the invention of the heating apparatus has been described and illustrated herein in specific terms and details of construction, arrangement and operation, various changes in and modifications of the same may be resorted to without departing from the spirit of the invention, or the scope of the claims appended hereto.

Having thus fully described the invention, what is claimed, is:—

50 1. An electrical heating apparatus comprising a closed water tight casing, a filling

of insulation material within said casing, a plurality of heating units embedded within said filling, said material of a characteristic capable of hardening around the units under the action of the heat therefrom, a conduit leading from said casing, and terminal conductors leading from said heating elements and extending outwardly of said conduit.

2. An electrical heating apparatus comprising a water tight casing, a filling of insulation material within said casing, a plurality of separate heating units embedded within said filling and each consists of a pair of connected heating elements, one extending in the other and each comprising a series of coils connected one in series with the other, a conduit leading from said casing, terminal conductors leading from said separate heating units and extending outwardly of said conduits, and switching devices carried at the outer end of said conduit for individually controlling said heating units.

3. An electrical heating apparatus comprising a plurality of separate units, each of said units consisting of a T-shape and a U-shape element, one extending into the other, and each comprising a series of coils connected one in series with the other, terminal conductors leading from each of said units and means for individually controlling each of said units.

4. An electrical heating apparatus comprising a casing, a plurality of separate units arranged therein and each consisting of a pair of connected heating elements, one of said elements being U-shape and the other T-shape and extending into the former, each of said elements comprising a series of coils connected one in series with the other, a body of insulation material arranged within the casing and having said units embedded therein, said material of a character to harden by the heat from said units, a terminal conductor leading from each of said units to said casing, and means for individually controlling each of said units.

In testimony whereof, I hereby affix my signature hereto.

GEORGE R. CONKLIN.
